MIXING CIRCUIT ARRANGEMENT

Adelbert van Weel, Eindhoven, Netherlands, assignor to Hartford National Bank and Trust Company, Hartford, Conn., as trustee

Application July 2, 1946, Serial No. 680,930
In the Netherlands March 27, 1943

Section 1, Public Law 690, August 8, 1946
Patent expires March 27, 1963

3 Claims. (Cl. 250—20)

1

This invention relates to a mixing circuit which is particularly suitable for short waves and in which the incoming oscillations are supplied in push-pull and the local oscillations in single phase arrangement to the input electrodes of two discharge systems (mixing systems). In the transmission of ultra-high frequencies this receiving method has the advantage of yielding a low input damping and a better signal-to-noise ratio.

A circuit of this kind exhibits the drawback, however, that the input impedance of the mixing systems, more particularly in receiving ultra-short waves, has only a small value, due to which the voltage having the frequency of the local oscillations and being set up between the input electrodes of each of these systems usually becomes too low. To supply as high as possible a voltage having this frequency to the input electrodes of the mixing systems the (single-phase) circuit, which is constituted by the impedances, pairwise connected in parallel, of the two halves of the push-pull circuit and the parallel-connected input impedances of the two discharge systems, jointly with the impedances common to the input circuits of the two systems is, according to the invention, tuned to the frequency of the local oscillations.

In the present case the expression "push-pull circuit" is to be understood to mean the assembly of impedances available between two not directly interconnected input electrodes of the discharge systems, in which are flowing currents having the frequency of the incoming oscillations, the expression "input circuit of a discharge system" being understood to mean all the impedances available between the input electrodes of a discharge system and in which are circulating currents associated with this system and having the frequency of the local oscillations.

In order that the invention may be clearly understood and readily carried into effect it will now be described more fully with reference to the accompanying drawing, representing several embodiments thereof.

Fig. 1 represents a mixing circuit which forms part of a superheterodyne receiver for short waves, in which the local oscillations are supplied in single-phase and the incoming oscillations are fed in push-pull connection to the mixing systems 1', 1'' through a tunable lecher-system. The oscillations captured by a dipole antenna 2', 2'' are supplied to two conductors 3', 3'' forming part of the said lecher-system, which by means of a short-circuit bridge 4 is tuned to

2

the frequency of the incoming high-frequency oscillations. The antenna 2', 2'' is connected to the lecher-system 3', 3'' in such a manner as to ensure optimum matching of the antenna to the mixing systems. The expression optimum matching is to be understood an adaptation by which either a maximum signal-to-noise ratio or maximum amplification is obtained. The conductors 3', 3'' are connected to the anodes of 10 the said mixing systems 1', 1'' consisting of two diodes incorporated in a single discharge tube. The cathodes of the two mixing diodes are interconnected and their junction is connected to earth through the intermediary of a source of 15 potential O in which the local oscillations are generated. Consequently, the incoming oscillations are supplied through the lecher-system in push-pull, whereas the local oscillations are fed, by means of so-called "cathode-injection," in 20 single-phase (in the same phase) to the input electrodes of the two diodes 1', 1''.

With this circuit, as has been stated above, it proves to be very difficult in practice to obtain 25 a sufficient voltage having the frequency of the local oscillations across the mixing systems.

According to the invention this difficulty is solved by tuning the single-phase circuit, which in the case under view is constituted by the parallel-connected input impedances of the two discharge systems (indicated in the drawing by the capacities 5', 5''), the pairwise parallel-connected impedances of the two halves of the push-pull circuit (in the present case the conductors 3', 3''), jointly with the impedances 30 common to the input circuits of both systems (in the present case the impedance of the conductors 3', 3'' with respect to the surroundings as well as the impedance of the local oscillator O), to the frequency of the local oscillations.

Fig 2 represents an embodiment of the invention in which this tuning can be realized in a simple manner. To this end the lecher wires 3', 3'' are lengthened by parts 6', 6'' and the ends are connected by an earthed short-circuit 45 bridge 7, the extension being given such a value (which may be effected by adjustment of the short-circuit bridge 7) that the single-phase circuit is tuned to the frequency of the local oscillations. As a result thereof series-resonance in 50 regard to the oscillator frequency occurs in the circuit constituted by the local oscillator O, the parallel-connected input impedances 5', 5'', the parallel-connected lecher lines 3', 3'' and 6', 6'' and the impedance of the said lines with respect 55 to earth, as a result of which the voltage having

this frequency across the capacities 5', 5'' and so the voltage between anode and cathode of any of the diodes acquires a maximum value.

If desired, the length of the conductors 6', 6'' may be made shorter than in the case illustrated or may be reduced even to zero by interposing an impedance, preferably a variable impedance, between the short-circuit bridge 7 and earth. The desired resonance can be achieved by adjusting this impedance to a suitable value.

Fig. 3 represents an embodiment of the invention in which this is reduced to practice, the lecher system 3', 3'', 6', 6'' being surrounded at the same time by shielding means 8 of which the end 9 remote from the mixing systems 1', 1'' is earthed. In this case the short-circuit bridge 7 of the extended lecher-system is not connected directly to earth but through the intermediary of a variable condenser 10, this condenser being so adjusted as to establish the desired resonance.

Fig. 4 represents an embodiment of the invention in which the lecher wires 3', 3'' are extended by the conductors 6', 6'', the shielding means 8 surrounding these wires. In this case the short-circuit bridge 7 can be shifted not only along the two lecher wires 6' and 6'' but also along the inner side of the shielding means 8 and connects the screening means and the lecher wires to earth. The aforesaid resonance can be established by a correct adjustment of the location of the short-circuit bridge 7. It is not strictly necessary to lengthen the two lecher wires by pieces 6', 6'' in the various examples; instead thereof a single wire, for instance, which applies at the middle of the short-circuit bridge 4 may be sufficient.

In the executional examples the location where the incoming oscillations are supplied to the push-pull circuit (in the present case the junction of the antenna and the lecher-system 3', 3'') may also be chosen arbitrarily. In choosing this location it may be contemplated whether it is desirable either to prevent radiation of the local oscillations or to attain optimum adaptation. In fact, when the antenna is not in a potential node in regard to the local oscillations, the local oscillations are radiated and, moreover, a variation in size of the antenna impedance has a reactive effect on the frequency of the local oscillator. Often, however, it is also desired to connect the antenna to the lecher system at such a point as to obtain optimum matching and consequently maximum amplification and a maximum signal-to-noise ratio respectively.

When distributing, however, the assembly of impedances constituting the single-phase circuit in a suitable manner with respect to the antenna junctions, radiation of the local oscillations by the antenna can be entirely or substantially entirely avoided in all cases.

Fig. 5 illustrates, by way of example, how this may be effected. Between the short-circuit bridge 7 and earth is interposed a preferably variable impedance 11, an impedance 12, which is preferably also variable, being connected between the mixing systems 1', 1'' and earth, in series with the local oscillator O; if desired, these impedances may consist of lecher systems.

By a suitable adjustment of the impedance 11 it can be achieved that the right half of the single-phase circuit, reckoned from the antenna junctions to earth, is tuned to the frequency of the local oscillations. In regard to the left half of the single-phase circuit, also reckoned from

the antenna junctions onwards, the same can be achieved by adjustment of the impedance 12. As a result thereof the whole of the single-phase circuit is tuned to the frequency of the local oscillations and, moreover, the antenna exhibits a minimum potential difference (of the frequency of the local oscillations) with respect to the surroundings and so radiates the local oscillations as little as possible and not at all when making use of no-loss impedances. In the aforesaid manner it is consequently feasible not only to prevent the radiation of the local oscillations but also to match the antenna in an optimum way to the mixing systems.

As mixing systems use may be made not only of diodes, but also of triodes, tetrodes and so on. Advantageously the two mixing systems may often be jointly incorporated in one discharge tube and, as the case may be, have one cathode in common.

What I claim is:

1. An electrical circuit arrangement for mixing a first wave and a second wave, comprising the following elements in series circuit arrangement and in the order named, a first impedance element, first and second mixing elements arranged in parallel relationship, a second impedance element having distributed electrical constants and being coupled in push pull relationship to said mixing elements and a third impedance element, means coupled in series with said impedance elements to apply said first wave in the same phase to said mixing elements, and means coupled to said second impedance element at a point of optimum matching to apply said second wave to said mixing elements, said first and third impedance elements being adjustable relative to each other to tune said series circuit to the frequency of said first wave and to provide at said second impedance element a point which is a potential node for said first wave substantially coincident to said point of optimum matching.

2. An electrical circuit arrangement for mixing a first wave and a second wave, comprising the following elements in series circuit arrangement and in the order named, a first impedance element, first and second mixing elements arranged in parallel relationship, a second impedance element having distributed electrical constants and being coupled in push-pull relationship to said mixing elements and a third impedance element, circuit means coupled in series with said impedance elements to apply said first wave to said mixing elements, and means coupled to said second impedance element at a first point thereon to apply said second wave to said mixing elements, said circuit means, said first impedance element, said mixing elements and the portion of said second impedance element between said mixing elements and said first point forming a first series circuit, the remainder of said second impedance element and said third impedance element forming a second series circuit, said first and third impedance elements being adjustable relative to each other to tune each of said first and second series circuits to the frequency of said first wave and to provide at said second impedance element a second point which is a potential node for said first wave substantially coincident to said first point.

3. An electrical circuit arrangement for mixing a first wave and a second wave, comprising the following elements in series circuit arrange-

ment and in the order named, a first impedance element, first and second mixing elements arranged in parallel relationship, a lecher-system having one end thereof coupled to said mixing elements in push-pull relationship and having a short-circuiting member for tuning said coupled end to the frequency of said second wave and a second impedance element, circuit means coupled in series with said impedance elements to apply said first wave to said mixing elements, and means coupled to said lecher-system at a point of optimum matching thereon to apply said second wave to said mixing elements, said circuit means, said first impedance element, said mixing elements and the portion of said lecher-system between said mixing elements and said point of optimum matching forming a first series circuit, the remainder of said lecher-system and said second impedance element forming a second series circuit, said first and second impedance elements being adjustable relative to each other to tune each of said first and second series

circuits to the frequency of said first wave and to provide at said lecher-system a second point which is a potential node for said first wave substantially coincident to said point of optimum matching.
